UNITED STATES PATENT OFFICE.

JOHN ALBAN BAGGER, OF STOCKHOLM, SWEDEN.

DETACHABLE BOAT-MOTOR.

1,283,035.

Specification of Letters Patent. Patented Oct. 29, 1918.

Application filed November 24, 1916. Serial No. 133,156.

13

To all whom it may concern:

Be it known that I, JOHN ALBAN BAGGER, a subject of the King of Sweden, residing at Stockholm, in the Kingdom of Sweden, have 5 invented a new and useful Improvement in Detachable Boat-Motors, of which the following is a specification.

In detachable boat motors a reversing device is previously known in which the propeller screw and its shaft are movable in the horizontal plane, so that it may be swung from its position for "forward" to its position for "back." This device is impracticable in so far that when being moved from 15 "forward" to "back" the propeller acts in a direction at right angles to the boat thus altering the course of the boat, which is a great disadvantage in view of the fact that the reversing device is mostly used when putting to at landing-stages, and so forth.

This disadvantage is completely eliminated by the present invention which is broadly characterized by this that the propeller is arranged to be swung at least 180° 25 in a vertical plane. The propeller can thus not act in lateral direction, hence it does not tend to alter the course of the boat, and the additional advantage is also attained that by adjusting the propeller in greater or 30 smaller angles to its horizontal position the propelling or reversing effect of the same may be regulated.

In the accompanying drawing an embodiment of the invention is shown by way of 35 example.

Figure 1 shows a side view of a boat with attached detachable boat motor provided with a reversing device for the propeller according to the invention. Fig. 2 shows to a 40 larger scale the gearing and reversing device between the motor shaft and the propeller shaft. Fig. 3 shows a vertical section of the same device. Fig. 4 shows a perspective view of the reversible member forming a 45 bearing for the propeller shaft.

The driving shaft of the motor is arranged in a sleeve 1 to which the rudder 2 is secured. The driving shaft is connected with the propeller shaft 3 through a suitable gearing journaled in a casing 4 at the lower end of the sleeve 1. According to the invention the propeller shaft is not immovably journaled in the casing, but it may be swung 50 in the vertical plane within an angle of about 180°, that is to say in the plane through the stem and the stern-post of the

boat if the motor is attached directly astern. The propeller may then be adjusted from its sternmost position into any angle all the way to its diametrically opposite horizontal 60 "back" position indicated in the drawing by dotted lines. This swinging of the propeller may be effected in any suitable manner, for instance as shown in the drawing, by means of a toothed rack 5 meshing at its lower end 65 with a toothed segment or a pinion 6 connected to the bearing of the propeller shaft in such manner that the shaft is swung when the gear-wheel is rotated. At its upper end in the vicinity of the motor the rack meshes 70 with a pinion secured to the shaft of a hand lever 7 adjustable on a toothed arc 8.

According to the embodiment of the gearing shown in Figs. 2 to 4 the sleeve 1 is secured at its lower end to a boss on the one 75 half of the casing 4 the other half of which is secured by means of screws 11 to a shield 12 on the first half. A ring 13 (Fig. 4) is journaled between the two halves of the casing 4, the said ring being fulcrumed on a 80 shaft 14 journaled in the walls of the casing. The ring 13 is provided with a bearing sleeve 14¹ in which the propeller shaft 15 is journaled, and is connected by means of arms 16 with the pinion 6 coaxing with 85 the toothed rack. The rack is preferably guided in a sleeve 17 projecting upward from the upper side of the casing 4. A similar sleeve 23 of suitable length may also be provided on the lower side of the casing 4 if 90 required owing to the length of the toothed rack. To the shaft 14 the bevel gear 18 is secured which meshes with the bevel gear 19 on the motor shaft 20, and the bevel gear 21 which is rigidly connected with the bevel gear 18 and meshes with the bevel gear 22 95 on the propeller shaft 15. By moving the rack 5 the ring 13 will thus be turned in one direction or the other, and the propeller shaft is swung correspondingly without 100 severing the driving connection between the motor shaft and the propeller shaft. In order to protect the propeller 9 in its various positions from shocks or other outside influence it is suitable to surround the same by a guard ring 10 arranged in such manner that the propeller is allowed to swing freely.

The device operates in the following manner. When the propeller occupies the position shown with full lines in Fig. 1, it propels the boat forward. When the propeller is swung downward so that the propeller

shaft occupies a vertical position, it has no propelling action but in this position it only tends to raise the stern of the boat. If the propeller is further swung into the horizontal position shown in dotted lines, the boat is driven back by the propeller. If the propeller is adjusted into an intermediate position between the vertical zero-position and the two horizontal extreme positions, it acts 10 more or less propelling or backing according to the angle of inclination. It is thus possible by means of the present device easily to maneuver a boat forward and backward with great or low speed, and also to stop the 15 boat without changing the speed or the direction of movement of the motor, and without the course of the boat becoming influenced.

I claim:

20 1. In a detachable boat motor, the combination of a motor shaft, a propeller shaft adapted to be driven thereby, and means whereby said propeller shaft may be swung relatively to said motor shaft through an arc 25 of approximately 180° in a substantially vertical plane for the purpose of making the propeller adjustable for driving the boat either forward or backward, or for stopping the same, without changing the direction of 30 movement or the speed of the motor and without influencing the course of the boat.

2. In a detachable boat motor, the combination of a casing, a motor shaft journaled in said casing, a member journaled in said 35 casing so as to be movable in a vertical plane about 180° relatively to the motor shaft, a propeller shaft journaled in said member, means for transmitting motion from said motor shaft to the propeller shaft, and 40 means for adjusting the position of said movable member in the casing, substantially as and for the purpose set forth.

3. In a detachable boat motor, the combination of a casing, a motor shaft journaled in said casing, another shaft journaled in the 45 casing at approximately right angles to the motor shaft, a member journaled on said shaft so as to be movable in a vertical plane about 180° relatively to the motor shaft, a propeller shaft journaled in the said member 50 at approximately right angles to the shaft of the same, means for transmitting motion from said motor shaft to the propeller shaft, a pinion attached to the said member, a rack journaled in the casing and meshing with said pinion, another pinion fulcrumed outside the casing and meshing with the rack, a hand-lever secured to said pinion, a pawl on said lever, and a toothed arc 55 cooperating with the said pawl for adjustment 60 of the position of said lever, substantially as and for the purpose set forth.

4. In a detachable boat motor, the combination of a casing, a motor shaft journaled in said casing, a bevel gear on said motor 65 shaft, another shaft journaled in the casing at approximately right angles to the motor shaft, a member journaled on said shaft so as to be movable in a vertical plane about 180° relatively to the motor shaft, a propeller shaft journaled in the said member at 70 approximately right angles to the shaft of the same, a bevel gear on said propeller shaft, a bevel gear on the said shaft in the casing meshing with the bevel gear on the 75 motor shaft, another gear on the said shaft rigidly connected to the first named bevel gear and meshing with the gear on the propeller shaft, a pinion on the said member, a rack journaled in the casing and meshing 80 with the said pinion, and means for adjusting the position of said rack, substantially as and for the purpose set forth.

JOHN ALBAN BAGGER.
